UNITED STATES PATENT OFFICE.

JOHN H. PARTRIDGE, OF KANSAS CITY, MISSOURI.

APPARATUS FOR USE IN DRAWING FERMENTED LIQUIDS FROM CASKS.

SPECIFICATION forming part of Letters Patent No. 309,561, dated December 23, 1884.

Application filed April 4, 1884. (No model.)

To all whom it may concern:

Be it known that I, JOHN H. PARTRIDGE, of Kansas City, Jackson county, Missouri, have invented a new and useful Improvement in Apparatus for Use in Drawing Fermented Liquids from Casks, of which the following is a full, clear, and exact description.

My invention relates to an apparatus for preventing the aeration of liquids in the process of withdrawing them from kegs or other vessels; and it consists of a metal tube having suitable diameter, and provided with a tapering bung-nozzle into which a packing-plug, also tapered and fixed upon a tube of smaller diameter, that is termed the "induction-tube," is adapted to be placed, and form an air-joint therewith. The induction-tube has fixed to one extremity an expandible rubber bag or similar instrument, the operation of which will hereinafter be more fully explained.

Reference is to be had to the accompanying drawings, forming part of this specification, in which similar letters of reference indicate corresponding parts in both figures.

Figure 1 shows the apparatus in a sectioned elevation, and Fig. 2 is a section through a barrel of liquid having the apparatus applied thereto.

Much inconvenience has heretofore attended the operation of drawing beer and wines from air-tight packages, for upon a quantity of the same being withdrawn from its cask the atmosphere enters and contaminates the whole.

In operation the screwed cap B is removed from the main tube C D, and the air-tube A jointed at P, and attached to the plug F at G' and to the inflatable vessel K by means of the nipple G and its clamping-disks H H'. The tubular bung E, which is screwed to the main tube C D, is fixed within the bung-opening of a keg or barrel, O. Then the rubber bag K is folded into a sufficiently small package, and, by means of the before-mentioned induction-tube A, is inserted down through the main tube, and forced therefrom into the liquid M, where it is inflated correspondingly as the liquid is withdrawn. Meanwhile the plug F has been forced to a tight point within the tapering bung E, and the entering atmosphere passes

down the induction-tube. The cap B serves, 50 mainly, to hold the induction-tube in a rigid position. By attaching a funnel of suitable size to the upper end of tube A, or by a similar arrangement, ice-water may be used as the inflating-fluid.

The arrows N N shown in the drawings indicate the direction in which the inflating-fluid enters the vessel.

The before-described inflatable vessel is preferably of such dimensions as to entirely fill the 60 cask. The main tube should be constructed of a sufficient length to readily contain the before-mentioned flexible vessel, so that when the apparatus is not in use the said tube answers the purpose of a shield for the said vessel, thereby 65 preserving the latter for future utility, and from any injury that it might otherwise receive. For instance, after all of the liquid has been withdrawn from a barrel or keg, and it is not desired to apply the apparatus immediately 70 to another, the main tube C D, together with the attached bung-piece E, and the induction-tube therein contained, are first sufficiently loosened in the bung of the barrel, and then carefully withdrawn until the flexible vessel 75 (which obviously becomes disinflated by the operation) is clear of the bung-hole, after which the said vessel is, by means of the induction-tube, drawn within the main tube, where, as before mentioned, it will be secure from the 80 ravages of insects and vermin.

The function of the cap B consists in guiding the outer end of the induction-tube A and in excluding insects from the interior of the main tube; but it is obvious that its form may 85 be greatly altered without changing the purposes for which it is intended, or its services may be dispensed with altogether. The opening through its center, through which passes the induction-tube, may, if desired, be provided with a packing-chamber, or it may be enlarged; but preferably, as shown, such opening has a diameter corresponding to the size of the said tube.

Having thus described my invention, I claim 95 as new and desire to secure by Letters Patent—

1. In the apparatus described, the combination of the main tube C D, the bung-piece

E, the cap B, and the induction-tube A, there-
in contained, substantially as and for the pur-
poses set forth.

2. In combination with an air-tight vessel of
5 liquid, the main tube C D, and the induction-
tube A, jointed at P, and having fixed there-
on the plug F, substantially as described.

3. The combination, with the main tube C

D, of the induction-tube A, the plug F, and the
flexible vessel K, substantially as described. 10

In testimony whereof I affix my signature in
presence of two witnesses.

JOHN H. PARTRIDGE.
